CLAIM

The ornamental design for a shoe, as shown and described.

DESCRIPTION

FIG. 1 is a top, left, and front perspective view of an ornamental design for a shoe;

FIG. 2 is a front elevational view of the shoe of FIG. 1;

FIG. 3 is a rear elevational view of the shoe of FIG. 1;

FIG. 4 is a left side elevational view of the shoe of FIG. 1;

FIG. 5 is a right side elevational view of the shoe of FIG. 1;

FIG. 6 is a top plan view of the shoe of FIG. 1; and,

FIG. 7 is a bottom plan view of the shoe of FIG. 1.

The broken lines illustrate portions of the shoe that form no part of the claimed design.
